METHOD OF REFRIGERATION

Joseph F. Winkler, Philadelphia, Pa.

Application July 11, 1941, Serial No. 401,899

2 Claims. (Cl. 62—178)

In the art of refrigeration it has heretofore been the practice to utilize a liquid or a gaseous refrigerant having the desired boiling point and coefficient of expansion, said medium being compressed and cooled to a certain extent and then permitted to expand or evaporate thus absorbing heat and effecting reduction in temperatures. Under this practice the pressure in the evaporator as well as in the condenser, and the critical temperature in the condenser, had to be maintained at requisite figures (which varied with the nature of the medium used) which in most cases were relatively high in the case of pressure and relatively low in the case of temperature if low temperature refrigeration was to be achieved. More specifically the evaporator side of the apparatus had to be maintained in a state of substantial vacuum in order to permit complete and rapid evaporation or expansion of the refrigerating medium so as to utilize to the maximum the heat absorbing capacity of the refrigerating medium. Even so, no real low temperature refrigeration was obtainable without especial apparatus, expensive in structure and maintenance and bulky and intricate in operation. It has also heretofore been proposed to use what is known as "binary" refrigeration in which a highly volatile, low boiling point medium, such as ammonia gas, was dissolved in another medium such as water having a higher boiling point and this method of refrigeration while having certain advantages is nevertheless limited in its effectiveness by the amount of ammonia gas that could be absorbed in a given amount of water at a given temperature, by the critical liquefying temperature of ammonia gas and by its coefficient of heat absorption. It is therefore the object of the present invention to produce a novel method or system of refrigeration in which two gaseous media are used, such gaseous media having widely diverging boiling points and critical liquefying temperatures, said refrigerating media being used in direct contact one with the other so that it may be said that said media are intermingled or "dissolved" in one another.

It is a further object of the present invention to produce a novel low pressure apparatus for carrying out the novel method referred to, the full nature and advantage of which will be more clearly understood from the following specification and the accompanying drawing in which:

Fig. 1 represents a diagrammatic view, partly in vertical section and partly in elevation, illustrating the general construction and operation of

the refrigerating apparatus embodying this invention.

Fig. 2 represents, on an enlarged scale, a vertical cross section of the control valve intermediate the expansion and compression sides of the apparatus.

Referring to the drawing in which like reference characters indicate like parts, 4 designates a pump casing having the low pressure cylinder 6 and the high pressure cylinder 8 in which operate respectively the pistons 10 and 12. The pistons 10 and 12 are actuated by the crank shaft 14 which is provided with the pulley 16 which is driven from any source of power (not shown), it being understood that any other means for driving the crank shaft 14 may be employed. The pistons 10 and 12 are provided with the check valves 18 and 20. 22 represents an outer condenser within which is enclosed the inner condenser 24, there being a space or chamber 26 formed therebetween. From the low pressure cylinder 6 a pipe 28 leads to the chamber 26 between the outer and inner condensers 22 and 24, and from the chamber 26 the pipe 38 leads back into the high pressure cylinder 8. From the high pressure cylinder 8 the pipe 40 leads into the inner condenser 24 which also contains the cooling coil 42 which is connected by means of the pipes 44 and 46 with the cooling apparatus 30 generally designated as 48 and which may be of any desired conventional type. 50 designates a fluid control or other valve mechanism which regulates the flow of the condensed refrigerating media 52 in predetermined quantities into and 35 through the pipe 56 to the expansion chamber 58 which is preferably insulated as at 60. 62 designates a pipe controlled by the valve 64 serving to carry the condensed lubricant 66 from the chamber 26 back into the crank case 68 of the pump assembly 4. If it is desired to use a series 40 of expansion chambers for successive utilization of refrigerating media, the pipe 70, which leads to the upper expansion chamber 72, is suitably connected either to the interior of the pipe 54, to the lower or next preceding expansion chamber 58, or to the pipe 56. Similarly, if it is desired 45 to utilize some of the higher boiling unevaporated refrigerant in the expansion chamber 58 for the purpose of relatively higher temperature refrigeration, the pipe 74 is used which leads to and through the pump 76 which is operated by the crank shaft 14, the refrigerant being then passed through the pipe 78 into and 50 through the cooling coil 80 from the other end of which the refrigerant returns to the expansion

sion chamber 58 by means of the pipe 82. The expended refrigerating medium is removed from the expansion chamber 58 through the pipe 84 and the control valve 86, which is shown in detail in Fig. 2. 88 designates a wick which extends into the pipe 84 leading to the valve 86 for a purpose hereinafter more fully explained.

Referring to Fig. 2, it will be seen that the valve 86 which communicates with the expansion chamber 58 through the pipe 84 also leads to the low pressure cylinder 6 through the pipe 90. The valve 86 comprises the stem 92 which carries the valve head 94 which is adapted to seat upon and close the throat 96 intermediate the inlet pipe 84 and the outlet pipe 90. The valve stem 92 is constantly urged upwardly by the spring 98 so as to keep the valve head 94 in an upper position and keep the throat 96 normally open. In this condition the bellows 102 is collapsed (upwardly) and the bottom plate 104 of the bellows is raised with respect to the bottom of the valve casing. This condition prevails until the pressure in the low pressure cylinder 6 and hence the pipe 90 has reached a predetermined limit, whereupon the pressure transmitted through the conduit 100 expands the bellows 102 and thus bears down upon and tends to compress the spring 98 thus causing the valve head 94 to engage its seat and close the throat 96 as shown in Fig. 2. Where a series of expansion chambers are used (such as the additional expansion chamber 12), the pipe 104 connects with the pipe 84 so that the expended refrigerating medium from the second (or third, etc.) expansion chamber 12 leads into the valve 86 through the common pipe 84.

The operation is as follows:

The inner condenser 24 is charged with a predetermined amount of selected gases having the desired characteristics, but in actual practice I prefer to use propane gas (C_3H_8) and ethane gas (C_2H_6) in the ratio of approximately 30% ethane and 70% propane. Propane, under one pound pressure, has a boiling point of approximately minus 45° F. while ethane at the same pressure has a boiling point of approximately minus 125° F. Propane will liquefy at a temperature of plus 90° F. (or less) and under compression of about 150 pounds, and ethane at about the same critical temperature will need about 750 pounds pressure in order to liquefy. By combining ethane with propane in about the ratio suggested, I am able to operate at a critical condenser temperature of plus 90° F. or less and at about 150 pounds pressure in the condenser or less. In other words, the combined ethane and propane will have the critical liquefying pressure and temperature of propane gas alone as long as the critical liquefying temperature of ethane (alone) which is about 90° F. is not exceeded. Why this is so, and whether or not a chemical reaction takes place, I cannot at this time explain. The fact remains that despite the individual characteristics of propane and ethane as above set forth when used alone, they do behave as I have explained and this has been established by the continuous, successful and efficient operation of a machine built according to the present disclosure and run for a considerable length of time under actual commercial production conditions. Also I have noted that by this arrangement the propane in the liquid state can be used as an auxiliary or relatively higher temperature refrigerating medium throughout the cycle of operation while the more volatile and lower boiling point ethane serves as the main or low temperature refrigerating medium. In actual

practice, and starting with a mixture or "solution" of ethane and propane gas as at 52, and with the pump 4 in operation, the refrigerating medium as controlled by the valve 58 passes through the pipe 54 into the expansion chamber 58 (and in the event of multiple expansion chambers into the chamber 12, etc.). Here the mixture of ethane gas and propane gas, under a pressure of about one pound, evaporates and results in the required heat exchange to refrigerate the receptacle 106 (and 108, etc.). Since some of the lubricant 66 inevitably passes through the system, the wick 88 is utilized which, by capillary action, continuously transfers liquid propane and the admixed lubricant from the expansion chamber 58 into the pipe 84. The mixture of evaporated ethane and propane together with any lubricant that may adhere thereto is compressed by the low pressure piston 10 through the pipe 28 into the chamber 26 where initial cooling takes place which results in precipitation of the lubricant into the lower portion of the chamber 26 as at 66. From the chamber 26 through the pipe 38 the partially cooled mixture of gases is drawn into the high compression cylinder 8 from which, through the pipe 40, the mixture is fed directly over the cooling coil 42 where it is condensed into liquid as at 52 to repeat the cycle. Excess lubricant collecting as at 66 is fed back into the crank case 68 through the pipe 62 and valve 64. Any unevaporated or liquid propane remaining in the expansion chamber 58 may, if desired, be utilized for secondary refrigeration by being conducted through the pipe 74 which communicates with the bottom of the expansion chamber 58, through the pump 76, the pipe 78, the cooling coil 80 and back through the pipe 82 into the expansion chamber 58. It will be noted that because liquid propane is heavier than liquid ethane, the communication of the pipe 74 with the bottom of the expansion chamber 58 will result in substantially pure liquid propane being drawn off through the pipe 74 and through the circuit including the expansion coil or cooling coil 80. The liquid propane flowing through the pipe 78, cooling coil 80 and pipe 82, evaporates and the vaporized propane mixes with the ethane which vaporizes in the chamber 58. By this means, the differential in the evaporation of the ethane and propane is compensated for and the mixture of 20 per cent ethane and 70 percent propane with which the system was initially charged, is maintained substantially constant.

By means of the apparatus described, and by the combination of ethane and propane in the ratios suggested, a refrigerating system is attained which operates under one pound pressure in the expansion chamber or chambers 58, 12, etc., under maximum pressure of about 150 pounds in the compression side of the apparatus, and at a critical temperature of 90° F. or less on the condenser side of the apparatus. Also by this means multiple refrigeration at different temperatures is attainable with automatic self-lubrication and automatic separation of the lubricant from the refrigerating medium. The evaporation of the ethane in the chamber 58 serves to maintain at least a part of the propane in the liquid state due to the latter's relatively higher boiling point so that the propane is available for use in the liquid state as a higher boiling refrigerant.

In order to equalize the pressure between the chamber 26 and the interior of the crank case 68, I utilize the small caliber pipe or conduit 108. The pressure-regulated valve 86 permits continu-

ous and uniform operation of the pistons 6 and 8 by preventing development of extreme pressure at any given point throughout the apparatus and also permits starting of the pump by a motor having a relatively low starting torque. Since ethane has a boiling point of about minus 125° F., it will be seen that when my refrigerating apparatus has reached its maximum rated efficiency very low temperature refrigeration, extending well below zero is attained and maintained. It will also be seen that in addition to direct and extreme refrigeration of any given object (106, 108, etc.) my refrigerating system and apparatus also provide relatively higher temperature refrigeration by use of the liquid propane which in that state has a temperature of minus 45° F. or less.

Having thus described my invention, what I claim as new and desire to secure by Letters Patent is:

1. The method of producing low temperature refrigeration which includes liquefying a mixture of ethane and propane in a closed circuit at a temperature of about 90 degrees F. and at a pressure of about 150 pounds per square inch in a first zone of said circuit, vaporizing all of said ethane 25

and a portion of said propane in a first expansion chamber, vaporizing the remainder of the propane in a second expansion chamber, mixing the vapors produced in both of said expansion chambers, returning said mixture of vapors to said first zone and reliquefying said mixture to start another cycle of operation.

2. The method of producing continuous low temperature refrigeration which includes mixing 10 a minor portion of a first gaseous medium having a relatively low boiling point and a relatively high liquefying pressure, with a major portion of a second gaseous medium having a relatively higher boiling point and a relatively lower liquefying 15 pressure at a predetermined temperature, liquefying the mixed gases at the liquefying pressure and temperature of said second medium, evaporating substantially all of said first medium and a portion of said second medium in a first expansion chamber, evaporating the remainder of 20 said second medium in a second expansion chamber, and remixing and reliquefying the vapors of said first and second media to start another cycle of operation.

JOSEPH F. WINKLER.
